UNITED STATES PATENT OFFICE.

CHARLES E. GODLEY, OF DETROIT, MICHIGAN, ASSIGNOR TO EDMUND AND JONES CORPORATION, OF DETROIT, MICHIGAN, A CORPORATION OF NEW YORK.

LAMP-MOUNTING.

1,252,684.

Specification of Letters Patent.

Patented Jan. 8, 1918.

Application filed November 23, 1916. Serial No. 132,944.

To all whom it may concern:

Be it known that I, CHARLES E. GODLEY, a citizen of the United States, and residing at Detroit, in the county of Wayne and State 5 of Michigan, have invented a new and Improved Lamp-Mounting, of which the following is a specification.

This invention relates to means for adjustably supporting electric lamps, particularly headlights for motor vehicles, and its 10 object is to so construct the lamp and its mounting that the lamp can be rotated about its axis and can be tipped up and down through limited arcs.

15 This invention consists in the details of construction illustrated in the accompanying drawing and particularly set forth in the claim.

In the accompanying drawing, Figure 1 20 is a side elevation of an electric lamp embodying my invention. Fig. 2 is a perspective of one end of the stem on which the lamp may be mounted. Fig. 3 is a view of a washer on the inside of the lamp. Fig. 4 is 25 a section on the line 4—4 of Fig. 3.

Similar reference characters refer to like parts throughout the several views.

The body or shell 1 of the lamp is shown 30 to be substantially parabolic and is formed with an opening or hole 2 in its lower side at some distance from its axis, through which opening the threaded end 3 of the stem 4 extends. An enlargement 5, preferably provided with a flat face 6, receives 35 the washers 7 and 8 which are prevented from turning on the stem. A nut 9 and collar 10 causes the washers to grip the wall of the body.

At the point of engagement of the washers, the central longitudinal section of the body is substantially a parabola while the transverse section at right angles thereto is

a circle. The washers fit this body and can slide around the body in the plane of the circular section and can also slide longitudinally in the plane of the parabolic section, when the nut 9 is slackened a small distance. But the washers cannot slide diagonally of these two planes unless the nut is slackened up a considerable distance. The result is that 45 when the lamp is mounted on the stem 4, it can be rotated through a few degrees in either direction on its focal axis and can also be tilted up and down a similar distance. This is of especial advantage in adjusting 55 the headlights of automobiles for by the use of the present mounting the beams of light from the headlights can be directed as desired.

By reason of the wall of the body being 60 rigidly held between the two washers 7 and 8, there is no more necessity for the usual rivets to secure the lamp to its support. The labor and material cost of this mounting is thereby reduced, while at the same time 65 an adjustable lamp is produced. In case of accident, the lamp can be easily removed and another substituted, a wrench for the nut 9 being the only tool required.

I claim:

70 In a lamp mounting, the combination with a paraboloidal body having an opening in its wall at some distance from its axis, a supporting stem of less diameter than the opening extending therethrough, and having a non-cylindrical portion where it passes through said opening, washers fitting non-revolubly on the non-cylindrical portion of the stem within and without the lamp body and closely fitting against the body, and a 75 nut on the end of the stem within the body to force the washers toward each other to grip the wall of the body.

CHARLES E. GODLEY.
